(57) CLAIM

We claim the ornamental design for a video camera with recorder and player, as shown and described.

DESCRIPTION

FIG. 1 is rear perspective view of a video camera with recorder and player of the present invention;

FIG. 2 is a front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line portions of the video camera are shown to illustrate environment only and form no part of the claimed design.
